W. S. WILLIAMS.
ELECTRICAL APPARATUS.
APPLICATION FILED DEC. 14, 1918.

1,310,042.

Patented July 15, 1919.

Inventor:
William S. Williams,
by *Alfred Davis*
His Attorney.

UNITED STATES PATENT OFFICE.

WILLIAM S. WILLIAMS, OF PITTSFIELD, MASSACHUSETTS, ASSIGNOR TO GENERAL ELECTRIC COMPANY, A CORPORATION OF NEW YORK.

ELECTRICAL APPARATUS.

1,310,042.

Specification of Letters Patent: Patented July 15, 1919.

Application filed December 14, 1918. Serial No. 266,752.

To all whom it may concern:

Be it known that I, WILLIAM S. WILLIAMS, a citizen of the United States, residing at Pittsfield, in the county of Berkshire, State 5 of Massachusetts, have invented certain new and useful Improvements in Electrical Apparatus, of which the following is a specification.

My invention relates to electrical apparatus and particularly to apparatus having windings supported about the legs of magnetic cores, such as are employed in transformers, reactances and the like.

The object of my invention is to provide 15 an improved means for retaining the windings in a predetermined spaced relation which is reliable, safe and readily manufactured.

When assembling windings about the leg 20 of a magnetic core, in the manufacture of electrical apparatus, it is necessary that certain predetermined spaced relations shall be maintained both between the winding groups and between the windings and the core; 25 hence to secure this end, spacing devices placed in both radial and axial directions are relied upon for maintaining the winding in the desired relations. Where the ends of the spacing devices extend beyond the edges of 30 the windings, it is generally customary to place distance pieces between these ends, or if the spacing device should have a bent over portion then the distance pieces are placed between the bent portion and the windings so 35 that the one device maintains the desired spacing effects in both directions. In either of these ways of putting in the distance pieces the mutual friction between the parts has generally been relied upon to retain the 40 spacing devices and the distancing parts completely intact. In drying, however, these parts not infrequently become loosened, and occasionally become displaced.

In the practice of my invention I have provided 45 a member for tying in such parts to avoid such displacement, the member being combined in such a way that it becomes a part of the spacing means without impairing its insulating qualities, whereby a rigid construction is consequently at all times provided.

For a more complete understanding of the

nature and objects of my invention reference should be had to the following detailed description when taken in connection with the 55 accompanying drawing in which:

Figure 1 is a view partially in section and partially in elevation of a winding assembled about the leg of a magnetic core in a manner embodying my invention; while Fig. 2 shows 60 a section of the device shown in Fig. 1 taken on the line 2—2 in Fig. 1. Fig. 3 is a view similar to Fig. 1 showing another embodiment of my invention; Fig. 4 being a section thereof taken on line 4—4. Figs. 5 to 11 65 show various forms of spacing devices employed in the practice of my invention. Fig. 12 shows a detail in the arrangement for tying together the parts. Fig. 13 shows a detail in the assembly of the windings and 70 spacing devices; and Fig. 14 shows my invention employed to secure spacing strips to insulating collars.

Referring now to Fig. 1 of the drawings, 10 denotes a magnetic core, of any suitable 75 type, on the leg 11 of which are mounted interleaved disk coil windings 12. These windings would be suitably connected as high and low voltage windings where the apparatus embodying my invention is a 80 transformer, to which type of electrical apparatus my invention will have its widest application.

The windings 12 are insulated from the core 11 by the inner insulating cylinder 13, 85 shown as interposed between the core 11 and the windings 12. An outer insulating cylinder 14 is provided to insulate the windings shown on leg 11 from other windings, or from exterior grounds such as the housing 90 which may inclose the apparatus, or from other portions of the core. For this reason portions of the ends of the cylinders are illustrated as closed by insulating material 15 inserted between the windings and adjacent 95 portions of the core.

The windings, however, are themselves maintained in a predetermined spaced relation, after they have been assembled by the spacing devices shown at 16 in order that 100 proper ventilation and insulation is at all times provided.

The spacing device shown at 16 may be any one of those which are in effect U-shaped

spacers shown in Figs. 5 to 11. The simplest form thereof is shown in Fig. 5 and consists of two independent leg members 20, having one or more distance pieces, or filling members 21 inserted therebetween at one end.

To secure these legs and fillers together, I form elongated openings 22 and 23 in the leg members and fillers respectively as shown in Fig. 12, and insert a tying member 24, which is in the form of a strip having a section whose cross-section snugly fits the openings 22 and 23; the tying member being formed or bent to lie along the leg members 20, so that it is consequently not easily displaced having once been properly placed in position.

The legs, tying member and fillers are preferably each formed of insulating material such as press-board, fiber or the like, the assembled spacer being adapted to be slipped over the edge of a winding. Those shown in Figs. 1 and 2 are slipped over the inner edge of each coil of the windings 12 and are spaced circumferentially 25 from each other by an angle of approximately 60 degrees.

By placing the spacers 16 over the inner edge of a winding disk, a solid insulating abutment is placed between the winding and the cylinder 13 so that a concentric arrangement of the windings about such cylinder is insured. The spacers 16, in this instance, are made also sufficiently long to extend beyond the outer edge of the winding disks 35 in order to maintain the external cylinder 14 in a spaced concentric relation to the windings. Obviously, however, the spacers 16 could be placed over the outer edge of the winding disks, or some placed over the 40 outer edge and some over the inner edge with the same results.

In assembly, when the winding disks have had the intended number of spacers properly placed about their edges, they are stacked concentrically, so that the sides of the spacers 16 abut as shown at 25 in Fig. 13; thus providing a solid abutment from one end of the winding stock to the other for any axial impulses imparted to the windings 50 on account of magnetic or other reactions between the windings.

In the spacers 16, the tying member 24 is of course narrower than the legs 20 so that in that in the portion of the winding stock shown in Fig. 13, it is seen that edges of these tying members are not flush with the edges of the leg members, in consequence of which a longer leakage path is provided from one winding disk to another over the 60 edge of the spacers than if all the edges had been flush.

Through the spaces about the windings 12, thus provided by the use of spacers 16, a cooling and ventilating medium, such for instance as oil or air, will circulate. The

passages shown in Figs. 1 and 2 permit of the unimpeded movement of such cooling and ventilating medium in both axial and radial directions over the windings.

Should it be desired to provide a greater 70 distance between two adjacent winding disks than is provided by the superposed thicknesses of the members 20 and 24 in spacers of the type shown in Fig. 5, as indicated in Fig. 13, the spacer to be employed would be 75 assembled with one or more additional leg members or fillers such as shown at 30 in Fig. 6 the thickness of which is added to the superposed thicknesses of the original parts. The spacer shown in this figure is assembled 80 in precisely the same manner as that shown in Fig. 5 and comprises, in addition to the three leg members, distance pieces 31 inserted between one such member on one side and two on the other all of which are 85 secured together by a tying member 32 snugly passing through suitably formed slits in the parts; the tying member being also formed to prevent it being readily displaced after assembly.

Were it desired to provide a narrower distance between adjacent winding disks than is afforded by the spacer shown in Fig. 5, a simple U-shaped member 35 combining the leg members and securing members in one, having slotted distance pieces 36 slipped thereover as shown in Fig. 7. Such a spacer, however, would preferably be reinforced by an exterior U-shaped member such as shown at 37.

To improve the circulation facilities for the cooling medium to be passed over the windings, it is sometimes desirable to use a spacer which does not have linear engagement with the assembled windings at all 105 points. In such an instance a spacer of the type shown in Fig. 8 might be employed.

On the leg members 40 on the side away from the windings whose edge is to be engaged by this form of spacer, are secured 110 protuberances or buttons 41 by means of rivets 42; which buttons and rivets should both be formed of insulating material. The legs 40 have interposed therebetween distance pieces 43, which are secured by a 115 short tying member 44. Exterior members 45 are, in this instance, shown tied in by member 44 and serve a purpose similar to a washer.

The protuberances on the legs of this type 120 of spacer, however, may be and preferably would be secured on the leg member by one or more tying members instead of by rivets where my invention is practiced. This preferred manner of securing protuberances is 125 illustrated in Figs. 9, 10, and 11, but particularly in Fig. 9.

Here the legs 50 are slotted across one and to receive a tying member 52 for securing the interposed distance pieces 51. In addi-

tion to the end slot, each leg member 50 has two longitudinal slots through the body portion over which are placed similarly slotted laminæ 53, made preferably of the same insulating material as the legs; the laminæ 53 forming each protuberance being secured by a pair of tying members 54 and 55. Each of the tying members 54 and 55 are similar to the tying member 52, but are placed back to back, the bent-over portions extending in opposite directions away from the slot. This mode of securing the protuberances prevents them from being readily displaced from the legs 50 in any direction, and has better insulating properties than that shown in Fig. 8.

When spaces, such as shown in Figs. 8 and 9 are used, they would not be spaced around the edge of the winding disk so as to abut one another in the winding stack, as shown in Figs. 1 and 2, but would be so placed that every other one would be omitted from the normal arrangement shown in the first figures. The disks having spacers of this type on their edges would be assembled in staggered relation so that the spacers on the adjacent disks would bear on a disk at the points from which the spacers were omitted. This arrangement is shown in Figs. 3 and 4.

In Figs. 3 and 4, 10' denotes a core having a leg 11' surrounded by disk windings 12' which are insulated interiorly from the core by a cylinder 13' and exteriorly by a cylinder 14' and from the yokes by inserted insulating pieces 15'. Each disk of winding has a spacer 16' of the general type shown in Fig. 9 spaced about the circumference at points substantially 120 degrees apart, as shown in Fig. 4. The under disk whose spacers are indicated by dotted lines would preferably have spacers having their protuberances placed thereon slightly displaced, as indicated on the spacer 16'', so as to provide support for all the turns in a coil.

The spacers on the top disk in Fig. 3 are seen to bear on the winding disk below at the points from which spacers have been omitted as shown at *a*, and so on throughout the whole stack of windings. Here again the spacers are shown as placed over the inner edges of the disks in order to have a solid abutment therebetween on the inner cylinder 13'.

It is obvious that where it is not necessary to take the precaution of preventing the protuberances on the legs from being readily displaced in all directions, a single tying member for securing the protuberances to the legs will suffice. Spacers having protuberances secured in this manner are shown in Figs. 10 and 11.

In Fig. 10, there is shown a leg 60 having three slits across it. The one across the end receives the tying member 62 for secur-

ing the distance pieces 61. Those through the body receive the tying members 64 which secure the laminæ 63 in place to form the protuberances.

In like manner, in Fig. 11, there is shown a leg 70 slotted across the end to receive a tying member 72 to secure the distance pieces 71, but in place of the two additional slots being placed across the body to secure the protuberances as in Fig. 10, two longitudinal slots are here employed a little to one side of the center line of the leg. This permits the tying members 74, which secure the laminæ 73 in place, to overlap the laminæ sufficiently to give an even bearing surface.

In Fig. 14 my invention is shown as applied to a portion of an insulating collar or barrier 80. Here the barrier 80 is provided with elongated openings near one edge, with which openings, the openings in the fillers 81 are placed in register. A tying member 82 is then passed therethrough to secure the whole; the barrier when thus provided with spacers being ready for assembly in a winding construction.

Those skilled in the art will readily understand that spacing devices such as I have described may be passed over the edge of cylindrical windings as well as disk windings, where it is desired to produce a winding structure for an electrical apparatus having predetermined spaced relations among the parts without employing parts liable to become easily displaced.

While I have here shown and described several embodiments of my invention which are, at present, the best means known to me for carrying the same into effect, I would have it understood that they are merely illustrative and that I do not mean to be limited thereby to the precise details shown, nor in the choice equivalent arrangements except as defined in my claims hereunto annexed.

What I claim as new and desire to secure by Letters Patent of the United States, is:—

1. In an electrical apparatus, the combination with windings composed of coils in assembled relation, of spacing means for said windings each comprising leg members extending over the edges of said coils, filling members, and a securing member arranged to form a self-retaining device.

2. In an electrical apparatus, the combination with windings composed of coils in assembled relation, of spacing means for said windings each comprising leg members extending over the edges of said coils, perforated filling members, and a securing member traversing the perforation in said filling members and forming in coöperation with said other members a U-shaped spacing device.

3. In an electrical apparatus, the combination with windings composed of coils in as-

- sembled relation, of spacing means for said windings each comprising leg members extending over the edges of said coils, perforated filling members, and a securing member traversing the perforations in said filling members, said securing member being formed to lie along the leg members and to resist displacement from the assembled position.
- 10 4. In an electrical apparatus, the combination with windings composed of coils in assembled relation, of spacing means for said windings each comprising perforated leg members extending over the edges of said 15 coils, perforated filling members having their perforations arranged to register with those in said leg members, and a securing member arranged to traverse the aforementioned perforations, thereby forming a unitary spacing device.
5. In an electrical apparatus, the combination with windings composed of coils in assembled relation, of spacing means for said windings comprising perforated leg members 25 extending over the edges of said coils, perforated laminar pieces having their perforations in register with those in said leg members and arranged at points to secure desired spacing effects, and securing mem-
- bers arranged to traverse the aforementioned 30 perforations.
6. A spacing device for electrical windings comprising leg members, perforated laminar elements coöperating with similar perforations in said leg members to secure a desired 35 spacing effect, and a tying member traversing the aforementioned perforations.
7. A spacing device for electrical windings comprising perforated leg members, perforated laminar elements assembled at desired points along said leg members so as to have the perforations in register, and a securing member snugly traversing the perforations and formed to resist displacement from the assembled position.
- 40 8. A spacing device for electrical windings comprising leg members having perforations across one end, and perforated distance pieces in register with the end perforations in the leg members, and a securing member having a U-shaped form passing snugly through the perforations and arranged to have its legs overlie said leg members.

In witness whereof, I have hereunto set my hand this 10th day of Dec. 1918.

WILLIAM S. WILLIAMS.
